United States Patent Office

Des. 194,098
Patented Nov. 20, 1962

194,098

DOOR

Danforth Cardozo, Jr., Weston, Conn., and Sidney H. Bradd, Jr., New York, N.Y., assignors to Simpson Timber Co., Seattle, Wash., a corporation of Washington

Filed Feb. 26, 1962, Ser. No. 68,971

Term of patent 14 years

(Cl. D13—1)

FIGURE 1 is a front elevational view of a door showing our new design;

FIG. 2 is a sectional view, with parts in elevation, on a larger scale than FIG. 1, and taken substantially on broken line 2—2 of FIG. 1; and

FIG. 3 is a view on the same scale as FIG. 2, is a sectional view with parts in elevation, and taken substantially on broken line 3—3 of FIG. 1.

The rear of the door is substantially like the front.

We claim:

The ornamental design for a door, as shown and described.
